United States Patent Office.

WILLIAM GORMAN, OF NEW BRITAIN, CONNECTICUT, ASSIGNOR TO THE RUSSELL
AND ERWIN MANUFACTURING COMPANY, OF SAME PLACE.

Design No. 4,335, dated September 6, 1870.

DESIGN FOR CUPBOARD-LATCH.

The Schedule referred to in these Letters Patent and making part of the same.

To all whom it may concern:

Be it known that I, WILLIAM GORMAN, of New Britain, in the county of Hartford, in the State of Connecticut, have originated and designed a new Design for a Cupboard-Latch; and I do hereby declare that the following specification, taken in connection with the drawing making a part of the same, is a full, clear, and exact description thereof.

Figure 1 represents a top elevation.

Figure 2, a side view.

The base-plate A, for both the bolt-case and the keeper, may be rectangular in form, or may have pointed ends, as shown. The outer edge of the base-plate is raised by a band, *a*, so as to give the effect of a sunken panel to the lip of the plate, and the space occupied by such panel is relieved by rosettes *b*.

The top edge of the bolt-case and keeper is also surrounded by a band like that around the base-plate,

and the sunken space so formed between such band and the base-plate, is occupied with lotus-leaf ornament in relief upon a matted ground.

The top-plate of the bolt-case and keeper shows, also, a sunken panel relieved by lotus-leaf scroll-work, as shown.

The button-head for the bolt is ornamented with a central rosette, and with leaves radiating therefrom.

The bolt-case and the keeper, when placed together as in fig. 1, show the complete design for the latch.

What I claim as my invention, and desire to secure by Letters Patent, is—

The ornamental design for a cupboard-latch, substantially as herein described and shown in the drawing.

Witnesses:

M. J. WOODRUFF,
H. E. RUSSELL, 2d.

WILLIAM GORMAN.
